AUTOMATIC CLEANER SOLUTION SUPPLY
FOR BEER DISTRIBUTING SYSTEMS

Benjamin Audia, Washington, Pa.

Application October 7, 1952, Serial No. 313,548

2 Claims. (Cl. 222—23)

1

This invention relates to an automatic cleaner solution supply for a beer distributing system and, more particularly to an electrical time controlled system whereby the pipes and coil of the beer distributing system is flushed with a cleaner solution automatically at predetermined intervals of time and for predetermined periods.

It is known that beer distributing pipes must be flushed from time to time with water, or better still, with a cleaning solution, such as a soda solution, in order to keep the lines and coil clean and fresh so as not to change the taste of the beer.

Various apparatus and systems have been devised in the past, generally manually controlled, for cleaning the pipes and coil when desired, but these have not proved satisfactory or fool proof, the judgment of the bartender often being depended upon for their proper operation. Moreover, such systems usually include complicated parts such as differentially operated valves and the like which add considerably to the cost and which often times become faulty in operation and are difficult to adjust and maintain.

An object of my invention is to provide an automatic timer controlled system for periodically flushing, with a cleaning solution, the pipes and coil of a beer distributing system without the aid or judgment of the bartender or other attendant, therefore, being devoid of human error or the effect of carelessness.

A more specific object of my invention is to provide an electrical system operated by a timer which can be preset so as to effect flushing of a beer distributing system with soda or other cleaning solution at periodic intervals of time without the necessity of operating the beer dispensing spigot, whereby, the bartender need not do anything in connection with the cleaning operations.

Other objects and advantages of my invention will become apparent from a study of the following description taken with the accompanying drawing, wherein the single figure shows, somewhat schematically, a beer distributing system embodying the teachings of my invention.

Referring more particularly to the drawing, numeral 1 denotes a beer keg which has the usual pipe extending into the top, thereof, which includes a valve 2. A hose 3 connected to a suitable source of pressure such as a compressed air tank (not shown) is connected to the pipe and introduces air under pressure into the beer keg so as to force the beer upwardly through pipe 4 thence

5 to the coil 5 which is enclosed in refrigerating tank 6. Cold water may be passed through the tank 6, or perhaps some other refrigerant, or the tank may be packed with ice, in order to cool the beer contained within coil 5. The cool beer is then dispensed through the spigot or tap 7.

In order to clean the beer system with a cleaning solution from time to time there is provided a mixing tank 8 on top of which is mounted a container or jug 9 which is filled with cleaning material, such as powdered soda, or perhaps some other cleansing solution.

Gravity flow of the material from jug 9 to tank 8 may be controlled by adjusting valve 8a, therebetween. Warm water is introduced into mixing tank 8 through a pipe 10 in regulatable amounts as determined by the setting of valve 11. The warm water inlet pipe 12 is fed from a hot water supply pipe and valve 13 and a cold water supply pipe and valve 14 so that by regulating the respective valves, any desired temperature of water may be fed through pipe 10 to the mixing tank 8. At the lower end portion of tank 8 there are provided a plurality of taps or outlets 15, 15a, 15b, and 15c, for the purpose of supplying a plurality of beer distributing units and cleaning solution. Only one beer distributing unit is shown for the purpose of clarity. It comprises a branch pipe 16 connected to outlet 15 through which the cleaning solution passes, thence through solenoid valve 17 and pipe 18 to pipe 4.

An electrical time controlled system is provided for effecting operation of various solenoid valves at predetermined time intervals. Such system includes a source of electrical potential, indicated by supply lines L₁, L₂, which may comprise a 110 volt household source, and across which is connected a timer motor 22 for operating a timer controlled switch unit 23 including contacts 24 and 25. Any conventional type of timer unit may be used which is well known, such as, for example, a Paragon 7-day calendar-dial time switch including a single pole double throw switch.

Normally, beer passes through the beer distributing system, that is, from the beer keg 1 through the open valve 2, normally open solenoid valve 26, pipe 4, coil 5, and finally through a dispensing spigot 7. Since solenoid valve 17 is normally closed it will stop the possibility of flow of cleaning solution from the mixing tank 8, to pipe 4. Normally solenoid valves 17 and 27 are also closed.

However, depending upon the setting of the 55 7-day calendar-dial time switch, operated by

timer motor 22, contacts 24 and 25 may be closed at predetermined intervals of time and for predetermined intervals of time and for predetermined lengths of time. For instance, they may close once a day, say early morning, at 8 o'clock, and for a period of 15 minutes, after which the contacts are automatically opened.

As contact 24 is closed a circuit is completed from line L₁, L₂, through electrical conductors 34 and 35 to energize solenoid coils 17 and 27. Energization and opening of solenoid valve 27 permits the liquid in coil 5 to discharge through a discharge pipe 28 into the drain pan 29 and finally through outlet 30 from which it may discharge into a sewer or other drainage system. At the same time, solenoid valve 17 is energized, thereby causing flow of cleaning solution from the mixing tank 8 through branch pipe 16, valve 17, pipe 18, pipe 4, through coil 5, thence through valve 27 and discharge pipe 28. Also at the same time by virtue of closing contact 25, a circuit is completed through solenoid valve 26 causing closing of said valve (since this valve is normally open) thereby stopping the flow of beer from keg 1 through pipe 4. Thus pipe 4 and coil 5 will be thoroughly flushed with cleaning solution which is drained without the necessity of opening spigot 7, therefore, not requiring the assistance of the bartender. Of course, the spigot 7 may also be flushed if opened by the bartender at this time. The occurrence of such flushing with cleaning solution will be called to the attention of the bartender by virtue of the lighting of the pilot light 31 during this period.

After a predetermined time interval of flushing, say about 15 minutes, depending on the setting of the timer mechanism, timer motor 22 will effect reopening of switch contacts 24 and thus deenergizing and closing solenoid valves 17 and 27 and deenergizing and opening solenoid valve 26 so as to shut off the supply of cleaning solution and the discharge pipe 28 and at the same time deenergizing solenoid valve 26 to effect opening thereof and restoring the flow of beer from beer keg 1 through pipe 4, coil 5, and spigot 7.

If it should be desired at any time to effect flushing of the coil 5 with a cleaning solution supplied by mixing tank 8 without awaiting initiation of this action by the timer motor 22, this can be done by manually closing switch 32 and switch 33 to complete the circuits through the various solenoid valves 17, 26, and 27 as well as through the pilot light 31. This will, of course, effect establishment of the necessary piping connections to allow the cleaning solution to flow from mixing tank 8 through pipes 16 and 4, coil 5, thence through discharge pipe 28 to the drain outlet 30. Upon manually opening switches 32 and 33, the various solenoid valves will be de-energized as well as pilot light 31, so as to re-establish the fluid connection from beer keg 1 through pipe 4, coil 5, to spigot 7.

In the event of power failure, or faulty operation of the various solenoid valves, manual control of valves in a branch circuit may be employed instead. More specifically should solenoid valve 17 become faulty in operation, it may be by-passed through the branch or parallel connection extending through manually controlled valve 19 and the hose or pipe 20. Thus by manually opening or closing valve 19, a fluid connection is either established or interrupted from mixing tank 8 to pipe 4. Similarly the same type of branch connection may be used to by-

pass solenoid valves 26 and 27, but are not shown for the purpose of simplicity.

For the purpose of simplicity only one beer keg 1 and coil 5 together with its flushing system is shown. It will be readily apparent that duplicate systems such as that shown, that is, involving additional beer keg coil and spigots as well as associated flushing circuits and the various solenoid valves, may be used. However, the same mixing tank 8 may be sufficiently large to supply a plurality of such systems through the various outlet connections 15a, 15b, and 15c. Stated differently, a duplicate hydraulic and electrical system may be used, identical to that shown on the drawing, for each of the other outlets 15a, 15b, 15c. They may all be mounted on a common base (not shown) so as to form, essentially, a single unit.

Thus it will be seen that I have provided a fully automatic, timed controlled system for periodically flushing the coil of a beer distributing system with a cleaning solution for predetermined time periods; furthermore, I have provided a beer coil flushing system which is automatically operable without the assistance of the bartender, therefore, which is fool proof and reliable; also I have provided a flushing system for cleaning the coil of a beer distributing system which is selectively controllable either by a time controlled mechanism or by manual controlled switching, or, in the event of power failure or faulty operation of the solenoid valves, may be controlled by manually operated valves; furthermore, I have provided an efficient mixing tank and piping assembly enabling selective mixture of different amounts of cleaning solution or materials with water at selectively different temperatures and which is effective to supply a plurality of beer distributing systems.

While I have illustrated and described a certain, specific embodiment of my invention, it will be understood that this is by way of illustration only, and that various changes and modifications may be made within the contemplation of my invention and within the scope of the following claims.

I claim:

1. Pipe flushing apparatus for a beer dispensing system including a keg, a coil adapted to be refrigerated, a spigot, and piping for normally causing the flow of beer from said keg through said coil and said spigot, said apparatus comprising, in combination, an electric control circuit including electrically operated valve means for said piping for normally causing the flow of beer from said keg through said coil, a mixing tank for storing a pipe cleaning material, hot water inlet and outlet connections for said tank, a timer controlled switch in said circuit for controlling said electrically operated valve means to interrupt said flow of beer from said keg to said coil and to simultaneously effect flow of said cleaning solution from said tank through said coil to effect flushing thereof, the duration of said flushing being controlled by the setting of said timer controlled switch, and signal means in association with said spigot and controlled by said timer controlled switch.

2. In a beer distributing system comprising a beer keg, a refrigeratable beer coil, a dispensing spigot, and a main supply pipe serially connecting said keg coil and spigot, apparatus for flushing said coil even when said keg is partially filled and without disconnecting said keg from said main supply line, said apparatus comprising, in

combination, a receptacle for storing and mixing a pipe cleaning solution, said receptacle supplied by hot and cold inlet water pipe connections and having an outlet connected to said main supply pipe at a point between said keg and coil, an electric control circuit including electromagnetic valve means for selectively providing a liquid flow path either from said receptacle to said coil or from said keg to said coil, an electric switch, a timer for controlling said switch and for operating said electromagnetic valve means upon expiration of a preset and preselected time period, and signal means in said circuit and closely associated with said spigot and controlled by said electric switch, whereby the bartender can be warned when said time period has ex-

pired and the coil flushing period has been completed.

BENJAMIN AUDIA.
